AIR CONDITIONING DEVICE

Edwin S. George, Detroit, Mich.

Application October 10, 1932, Serial No. 636,997

10 Claims. (Cl. 261—103)

The present invention pertains to a novel air conditioning device for treating the air both in summer and in winter. The principal object of the invention is to provide a device of this character suitable for home, office and factory use, which may be built and sold at comparatively low cost and which is readily portable from place to place.

The device is used in summer as an air cooler and dehumidifier by blowing a stream of air along one or more tanks containing ice or refrigerating units, the proper mechanism for these functions being contained within the apparatus. In the winter, the tanks are filled with water, and water drained therefrom is heated, elevated and discharged upon a screen lying over the tanks and the blower fan. The water forms a film on the screen, and the fan blows a current of air through the screen, whereupon the air is humidified and filtered of dust. In this connection, one of the important characteristics of the device is that no pump or other mechanical means is required to elevate the water. The heating element which causes the water to rise also warms the water so that it is more readily taken up by the current of air and further contributes to the heating of the room.

The invention is fully disclosed by way of example in the following description and in the accompanying drawings wherein;

Figure 1 is a longitudinal vertical section of the device;

Fig. 2 is a front end view;

Fig. 3 is a transverse vertical section, and

Figs. 4 and 5 are plan sections on the lines 4—4 and 5—5 respectively of Fig. 1.

Reference to these views will now be had by use of like characters which are employed to designate corresponding parts throughout.

The device is supported upon a hollow rectangular base member 1 which rests on rollers or casters 2. Another hollow rectangular frame member 3 of angle iron is suitably secured upon the base member 1, as by welding, as illustrated more clearly in Fig. 3.

The cabinet proper includes a rectangular wall 4 of sheet metal mounted upon the base 1 around the angle frame 3 and suitably secured to the outer vertical web thereof. The top of the cabinet consists of a removable cover 5 mounted upon the upper edge of the wall 4.

Within the wall 4 are mounted a suitable number of uprights 6 which have their lower ends fastened or welded to the member 3. Supporting brackets 7 are secured to the uprights 6 for

the purpose of supporting a rectangular frame 8, as illustrated in Figs. 3 and 5, for the purpose which will presently appear.

A pair of tanks 9 are disposed within the cabinet, slightly above the frame 8, and are supported from the uprights 6 by means of bolts 10. The tanks extend lengthwise of the cabinet and are spaced from each other as at 11 and also from the wall 4 by means of heat insulators 12 surrounding the bolts 10. The tanks may also be joined together at the inner walls and at the upper corners by suitable ties 13 as shown in Figs. 1 and 3. Drip tanks 14 are suspended from the frame 8 and are mounted to lie immediately below the tanks 9 as more clearly shown in Fig. 3.

Upon the tanks are mounted brackets 15 which support a screen 16 overlying both tanks. A solid shield or deflector 18 is secured upon the screen in such a manner as to cover the space 11 between the tanks 9 for a purpose which will presently be described.

A T-coupling 19 is placed at the bottom of the space 11 in communication with ports 20 in the inner walls of the tanks 9. The lower end of the coupling is connected by a line 21 to a chamber 22 in the bottom of the cabinet. The chamber 22 is in turn connected by a line 23 to a horizontal pipe 24 secured along the axis of the lid 15, and directly over the shield 18. The pipe 24 is formed with holes 25 in its bottom, and the rear end is closed by a plug 26. The coupling 27 which connects the pipes 23 and 24 may readily be removed.

Within the casing 22 is mounted a conventional electric heating element 28 which, however, may be replaced by any other suitable water heating means such as a gas burner. In the line 21 is mounted a flap type check valve 29 adapted to open in the direction from the T 19 to the housing 22 and to close in the opposite direction.

An electric motor 30 is supported on transverse bars 31 resting on rubber mountings 32 on the base member 3. The shaft 33 of the motor is vertical and carries a horizontal fan 34 disposed beneath the tanks 9.

On the front wall 35 of the cabinet are mounted two electric switches 36 and 37. A lead-in wire 38 passes through both switches in series and is connected to one end of the heating element 28. A fuse 39 is inserted in this conductor and is secured to the casing 22 in close proximity to the heating element but is obviously insulated from the casing as indicated by the numeral 40. The other lead-in wire 41 is connected to one of the terminals 42 of the motor and is branched

at 43 to the remaining terminal of the heating element. Finally, another conductor 44 extends from the remaining terminal 45 of the motor into the conductor 38 at a point between the switches 36 and 37. It will be apparent that the switch 37, when open, cuts out both the motor and the heating element while the switch 36, when open, with the switch 37 closed cuts out only the heating element. Current passing through the switch 37 flows along the conductor 44 to the motor 30.

A pair of swivel drain cocks 46 are fitted to the tanks 9 at the bottom thereof, and a pair of similar cocks 47 are fitted to the tanks 14. Normally, these cocks lie entirely within the wall 4 and occupy the position shown in dotted lines in Fig. 2. Adjacent these cocks, the front wall 35 is fitted with a door 48 having its upper edge hingedly supported at 49 and its lower edge provided with a hand latch 50 adapted to lock on the wall 35 as shown in Fig. 1. In order to drain the tanks, the door 48 is lifted and the cocks 46, 47 are swung outwardly to the position shown in Fig. 1.

The device is used as an air cooler and dehumidifier in summer and as a humidifier in winter. As a cooler and dehumidifier, the device is operated by filling the tanks 9 with crushed ice, or fitting them with mechanical refrigeration units, and starting the motor 30. The heating element is cut out, and the proper adjustment is made by closing the switch 37 and opening the switch at 36. Air is drawn into the cabinet through the open bottom thereof and blown by the fan upwardly along the tanks 9, escaping through openings 51 in the lid 5. The air is obviously cooled in passing along the tanks, and approximately 20% to 25% of the moisture in the air is condensed on the cold walls of the tanks. This condensed moisture drains into the drip tanks 14 from which it may be removed through the cocks 47. Also the melted ice may be drained from the tank 9 through the cocks 46. The structure supported upon the tanks is not used and may be removed on loosening of the coupling 27. The upper end of the pipe 23 is preferably plugged, and the water which flows from the tanks into the pipe 21, casing 22 and pipe 23 does not overflow the pipe 23.

When the device is used in winter as a humidifier, the upper structure is replaced by connection of the pipes 24 and 23 at the coupling 27 in the manner shown in Fig. 1. The tanks 9 are filled with water, and current is supplied to both the heating element 28 and the motor 30 by closing the switches 36 and 37. Water flows into the housing 22, and, on being heated by the element 28, is raised to the pipe 24. From the pipe 24 it is distributed over the screen 16 on which it forms a thin film. It will be seen in this connection that the part of the screen lying immediately over the space 11 is protected by the shield 18 so that no water falls therein. The air which is blown upwardly by the fan 34 absorbs some of the water from the screen and is discharged in humidified condition through openings 52 in the top of the lid 5. Shields 53 are pivotally supported in the corners of the lid between the openings 51 and 52 and may be held over either pair of openings by means of off-center springs 54. In the event that the steam pressure in the housing 22 exceeds the water pressure in the tanks 9, the check valve 29 closes the pipe 21 to prevent back flow of water into the tanks.

In summer the lateral openings 51 are uncovered so that the cooled, humidified air will be blown laterally into the room rather than into

upper regions where it is less necessary. In winter, however, it is preferred to blow the humidified air into the upper regions so that it will distribute more uniformly in the intermediate or occupied zone of the room.

Although specific embodiments of the invention have been illustrated and described, it will be understood that various alterations in the details of construction may be made without departing from the scope of the invention, as indicated by the appended claims.

What I claim is:

1. An air conditioning device comprising a pair of spaced tanks adapted to contain either water or a refrigerating medium, a water-retaining medium mounted over said tanks, means for delivering water from said tanks to said retaining medium and terminating in an apertured pipe disposed above said retaining medium, and a shield inserted between said pipe and said retaining medium, partly covering the latter and disposed directly over the space between said tanks.

2. An air conditioning device comprising a tank, said tank being constructed of heat conducting material and having a large external surface and being adapted to contain a quantity of water, said water being at a temperature lower than that of the surrounding air, means for creating an artificial current of air and for directing it against external surface of said tank whereby moisture in said air condenses on the surface of said tank, means for receiving the condensed moisture from the surface of said tank, and means adapted to cause cessation of said moisture condensing function and for humidifying said artificially created air stream, said means comprising a screen over said tank and in the path of said air stream, means for pumping water from said tank and for distributing it on said screen through which it passes to return to said tank, and heating means in the circulating system thus formed and adapted to raise the temperature of said water to a temperature higher than that of the surrounding air.

3. An air conditioning device comprising a pair of tanks spaced apart in a manner to define a passage with the surfaces thereof, said tanks being adapted to contain a quantity of water at a temperature lower than that of the surrounding air, means for creating an artificial current of air and for directing it through the passage defined by said tanks whereby the moisture carried by said air is condensed on the sides of said tanks, means beneath said tanks for receiving the condensed moisture, and means adapted to cause cessation of said moisture condensing function and for humidifying said artificially created current of air, said means comprising a water retaining medium mounted in the path of said air current, means for pumping water from said tanks and for distributing it onto said water retaining medium, said retaining medium being arranged so that excess water falls therefrom into said tanks, and a heating element in said pumping means and adapted to raise the temperature of the water in said tanks, pumping means and on said retaining medium to a temperature higher than that of the air stream.

4. A humidifier comprising a pair of spaced apart tanks arranged to define an air passage and adapted to contain a quantity of water, means for creating an artificial air current through said passage, a screen supported above said tanks and in the path of said air currents, means for pumping water from said tanks and for distributing

it onto said screen, and means for raising the temperature of said water being pumped to a point above the temperature of the air current.

5. In air conditioning apparatus, wherein the air is de-humidified in presence of higher temperatures and humidified in presence of low temperatures of the air, a self-contained unit comprising a casing having an open bottom and a relatively closed top, a fan positioned in and receiving its air supply through said open bottom, said fan being adapted to provide an upward flow of air within the casing toward the top, a pair of tanks supported in the casing and positioned in spaced relation to each other and to said flow path
- 10 to provide a definite width to the flow path between the tanks, a baffle above and spaced from the exit end of such definite flow path, a meshed element projecting laterally of such baffle, a water heating unit below and adapted to receive its water from the tanks, a water conduit having a trickle discharge portion above said meshed element and connected to the heating unit, air discharge openings in the top zone of the casing, and means for controlling the operation of said
- 15 fan and heating unit, whereby apparatus operation with water as the tank content and both fan and heating unit active the meshed element will be subject to the trickle discharge to produce humidifying characteristics to the air passing through said meshed element, and whereby apparatus operation with the fan active and heating unit inactive and with a refrigerant as the tank content air passing through the definite flow path
- 20
- 25
- 30

will be subject to de-humidifying action by heat exchange through the tank walls defining the path.

6. Apparatus as in claim 5 characterized in that the self-contained unit is mounted on casters to provide for portability and to locate the bottom plane of the casing above the floor plane, whereby the air supply for the fan will be provided from the floor zone of the room being air-conditioned.

7. Apparatus as in claim 5 characterized by a trough-like member below each tank to receive drippings, with the opposing inner walls of the members positioned to form a mouth for the definite flow path.

8. Apparatus as in claim 5 characterized in that the outlet openings for the top zone are in two series one of which opens through the top of the casing and the other opening through the side of the casing, means being provided to render one series active while the other series is inactive.

9. Apparatus as in claim 5 characterized in that the connection between tanks and heating unit is automatically controlled to limit movement of water therethrough to transfer from the tanks.

10. Apparatus as in claim 5 characterized in that fan operation and heating unit activity is by electrical means with the casing carrying external circuit make and break structures co-operative with circuits to said fan and heating unit to render them active and inactive at will with activity of the heating unit limited to periods of activity of the fan.

EDWIN S. GEORGE.
